UNITED STATES PATENT OFFICE.

GEORGE W. WILSON, OF READING, OHIO, ASSIGNOR TO THE AMERICAN LAUNDRY MACHINERY COMPANY, OF CINCINNATI, OHIO, A CORPORATION OF OHIO.

DOOR-CLOSING MECHANISM FOR DRY-CLEANING WASHING MACHINES.

Application filed May 25, 1923. Serial No. 641,527.

To all whom it may concern:

Be it known that I, GEORGE W. WILSON, a citizen of the United States, residing at Reading, in the county of Hamilton and State of Ohio, have invented certain new and useful Improvements in Door-Closing Mechanism for Dry-Cleaning Washing Machines, of which the following is a specification.

10 This invention relates to the class of washing machines used for cleansing garments with gasoline and more particularly to that type of machine in which means is provided for automatically preventing spreading of fire.

15 The objects of this invention are to provide such a device in which the melting of a fuse will automatically set into operation certain mechanism which will close the door 20 of the container so as to prevent spreading of the fire beyond the confines of the washing machine casing; and to provide also means for automatically closing the flue of the machine casing so as to prevent ingress 25 of air to the container and thereby smother the fire in the container.

Other objects of the invention will appear from the following description and claims when considered together with the drawings.

30 Fig. 1 shows in part an end elevation of my improved device applied to a washing machine; Fig. 2 is a sectional view showing the details of my improved device taken on line 2—2 of Fig. 1; and Fig. 3 is a detail view taken on line 3—3 of Fig. 2.

This invention constitutes a modification of the invention disclosed in the application, Serial No. 642,505, filed May 31, 1923, by Howard C. Curtiss.

40 The type of washing machine to which the present invention relates is well known in the art and comprises the outer casing 1 in which is rotatably mounted the container 2, this container being operated by means of suitable mechanism as indicated in a general way by reference numeral 3. The outer casing is provided with an opening 4 permitting access to the interior thereof and this opening is adapted to be closed by the door 5 which is hinged at the point 6.

The door 5 in open position rests against the stops 7^a which are adjustably mounted on the supports 7 suitably secured upon the top of the outer casing. The bolts 7^c permit adjustment of stops 7^a. The means for automatically closing the door comprises the arms 8 which are actuated so as to engage the door and force the same past the vertical dead center so as to permit the door to then close by gravity. The means for automatically actuating the arms 8 comprises the fusible link connection 9 which may be of any suitable form, preferably that illustrated in the Curtiss application above referred to, this link being connected by means of the wires or rods 10 to the lower ends of the upwardly extending stems 11. Apertures 12 are provided in the top wall of the machine casing for the stems 11 and plate members 13 are also provided for the purpose of maintaining the openings 12 closed at all times during the operation of the device. The stems 11 extend through apertures in the plates 13 and are connected at their upper ends to the cam members 14 which are fixed upon the reciprocating rods 15. These rods are mounted for movement in the base portions of the supports 7. The springs 17 abut at their ends against the portions 7^b of the supports 7 and at their other ends against the collars 18 which are fixed upon the rods 15. When the parts are in normal position as indicated in Fig. 2 the springs 17 are held under compression. The cam members 14, when released by melting of the fuse and action of the springs 17, are forced into engagement with the overlying end portions of the lever arms 19 which in each case is pivotally mounted within the base portions of the supports 7, as indicated at the point 20. The other end of each lever arm overlies and is adapted to be brought into engagement with the end portion of the lever arm 21 which is fixed upon the shaft 22. The shaft 22 is in turn rotatably mounted within the base portion of the support 7 and has fixed thereon the arms 8 which are adapted to engage the door 5 for closing the same. The lever arm 21 is provided with a spring 23 engaging the

other side thereof and having abutment against the base portion of the support 7 so as to tend to maintain the arms 8 away from and out of engagement with the door 5.

5 In case of fire causing the melting of the fuse 9, the rods 15 are forced outwardly by means of the tension of the springs 17, the plates 13 sliding over the openings 12 as the stems 11 move therewith. In this 10 way the cams 14 engage underneath the ends of the levers 19 and cause the same to be rocked in a counter-clockwise direction, as viewed in Figs. 1 and 3 of the drawing. This causes rotation of the levers 21 in a 15 clockwise direction as viewed in the same figures, and forces the arms into engagement with the door 5 for closing the same in a manner already described.

There is provided also on one end of the 20 container casing the flue 24, which is secured thereto by means of the bracket 25, for supplying air to the inside of the casing. The damper 26 is fixed upon the shaft 27 which is rotatably mounted in the flue and 25 the other end portion of the bracket 25. Fixed upon the shaft 27 there is provided the upwardly extending lever arm 28 which has also a depending portion 29 connected by means of the spring 30 with a portion 30 of the bracket 25 for normally maintaining the damper in open position, as indicated in Fig. 2.

In case of fire, outward extension of one 35 of the rods 15 will cause its bevelled end to engage the lever arm 28 and thereby effect closing of the damper 26 against the tension of the spring 30. In this way the fire within the casing is cut off from outside air.

40 It will be seen that in the present form of device practically the entire train of mechanism for closing the door as well as the damper is located outside of the casing, except for the fuse itself and the connections from the fuse to the upwardly extending stems which carry the cams. As a result of this arrangement ready access can 45 be had to the mechanism and furthermore practically the entire inside space in the 50 container is left unobstructed.

What I claim is:

1. In a machine of the class described, 55 the combination of a container for inflammable material, said container having an opening, a door for said opening, and thermally controlled means including actuating cam means located outside of said container for automatically closing said door in case of fire.

60 2. In a machine of the class described, 65 the combination of a container for inflammable material, said container having an opening, a door for said opening, and thermally controlled means including a heat responsive member located inside of said

container and a cam member located outside of said container for automatically closing said door in case of fire within said container.

3. In a machine of the class described, 70 the combination of a container for inflammable material, said container having an opening, a door for said opening, and thermally controlled means for automatically closing said door, including a reciprocatory 75 cam member located outside of said container, a heat responsive member located inside of said container, a connection between said heat responsive member and said cam member, and means associated with 80 said connection for maintaining said container closed at all times at the point where said connection extends through said container.

4. In a machine of the class described, 85 the combination of a container for inflammable material, said container having an opening, a door for said opening, and thermally controlled means for automatically 90 closing said door, including a reciprocatory cam member outside of said container, means normally tending to close the door, said means including a spring actuated cam located outside of said container, a heat responsive member located inside of said 95 container, and a connection between said heat responsive member and said cam member.

5. In a machine of the class described, 100 the combination of a container for inflammable material, said container having an opening, a door for said opening, and thermally controlled means for automatically 105 closing said door, including a heat responsive member and cam means connected therewith, said heat responsive member and cam member being located one on the inside and the other on the outside of said container.

6. In a machine of the class described, 110 the combination of a container for inflammable material, said container having an opening, a door for said opening, and thermally controlled means for automatically 115 closing said door, including a reciprocatory cam member outside of said container, a heat responsive member located inside said container, a connection between said heat responsive member and said cam member, and slid able means associated with said connection for maintaining said container closed at all times at the point where said connection extends through said container.

7. In a machine of the class described, 125 the combination of a container for inflammable material, said container having an opening, a door for said opening, and thermally controlled means for automatically closing said door, including a reciprocatory cam member outside of said container, a 130 heat responsive member located inside said

container, a connection between said heat responsive member and said cam member, said container having an opening through which said connection extends, and a slide 5 plate larger than said opening and through which said connection extends so that the said plate will move in response to the

actuation of said connection, whereby said opening is maintained effectively closed at all times.

10

In testimony whereof I hereby affix my signature.

GEORGE W. WILSON.
